(57) **ABSTRACT**

A new and distinct variety of artichoke (*Cynara cardunculus* var. *scolymus* L.) plant named 'PAGA 13-1', particularly characterized by its high yield, large primary bud size, large number of secondary and tertiary buds, wide bracts with fleshy base, thick stems, and late maturity, is disclosed.

10 Drawing Sheets

1

ARTICHOKE PLANT NAMED 'PAGA 13-1'

Latin name:

Botanical classification: *Cynara cardunculus* L. var. *scolymus*.

Varietal denomination: Varietal denomination of the claimed artichoke variety: 'PAGA 13-1'.

BACKGROUND OF THE INVENTION

Artichoke (*Cynara cardunculus* L. var. *scolymus*), or globe artichoke, is a thistle-like perennial plant native to the Mediterranean region and is a member of the family Asteraceae. Artichoke belongs to the species *Cynara cardunculus* L. that includes two subspecies/cultivation groups: the cardoon (*Cynara cardunculus* L. var. *altilis*) that is cultivated for its edible leaf stems, and the artichoke that is cultivated for its edible immature inflorescence hereinafter referred to as buds, heads, or capitula. In some instances, artichoke is distinguished as *Cynara scolymus*.

Artichoke is a popular vegetable food source in many regions of the world, with nearly two million tons of artichokes produced annually. The United States produces approximately 40,000 tons of artichokes annually, with California being responsible for nearly 100% of its production, of which about 80% is grown in Monterey County.

Historically, a common perennial artichoke variety that is grown in the United States is 'Green Globe', also referred to as an "Heirloom" artichoke. Despite the use of it as a traditional cultivar, 'Green Globe' does not produce large numbers of large buds which are most desired by consumers. Further, 'Green Globe' exhibits a substantial amount of phenotypic variation as well as protracted and unpredictable harvest intervals.

Thus, there exists a need for improved artichoke varieties having large sized post-primary bud production, programmable and predictable harvest timing, and better uniformity. The present artichoke variety described herein is a product of the efforts to develop such artichoke varieties.

BRIEF SUMMARY

The present disclosure relates to a new and distinct artichoke variety (*Cynara cardunculus* L. var. *scolymus*) which has been denominated as 'PAGA 13-1'. This new artichoke variety exhibits increased bud yield, size and plant vigor compared to 'Green Globe', and produces a large primary bud, about 10-19 secondary buds, and about 10-16 tertiary buds per primary reproductive shoot. Up to 6 of the primary and secondary buds are 12-15 inches in circumference. Between 4-5 of the secondary and tertiary buds are 10 $\frac{3}{4}$ -12 $\frac{1}{2}$ inches in circumference or larger. The remaining buds are generally between 3-10 $\frac{1}{2}$ inches in circumference. The plants produce between 4 and 10 reproductive shoots, in addition to the primary reproductive shoot, in the first production cycle. These secondary reproductive shoots produce less marketable sized buds than the primary shoot, although cultural practices such as cutting the primary reproductive shoot from the plant after harvest can materially increase the size and number of buds produced by these secondary shoots.

The new artichoke variety described herein is the product of an artichoke plant improvement program conducted over a number of years. The original parent is the unpatented *Cynara cardunculus* L. var. *scolymus* variety 'Green Globe', commonly known and cultivated in Castroville, Calif. for more than 90 years. This improvement project began with

2

the objective to develop an artichoke variety with superior bud production. This included selecting for improvements in both commercial quality of buds, as well as overall bud consistency and large size bud production per plant. Additionally, plants were selected based on their predictable and condensed harvest phase.

The new artichoke variety described herein was discovered after several years of isolating and propagating artichoke variety 'Green Globe' in Castroville, Calif. From this continual propagation, several selections were identified which exhibited superior yield characteristics as compared to 'Green Globe'. During this process, no crosses were made between 'Green Globe' and another artichoke variety, and these identified selections with superior yield characteristics were presumably results of natural mutations of 'Green Globe'. After identifying the superior quality plants from field conditions, the highest quality plants were selected for induction into laboratory tissue culture reproduction. These tissue-cultured plants were then planted in a test field in Castroville, Calif., where further selections were made among the population. Selections from this field were propagated by tissue culture, with subsequent field selections and tissue culture propagation conducted. The variety described herein as 'PAGA 13-1' is a final product obtained from these selections and tissue culture propagation cycles.

Artichoke plant 'PAGA 13-1' was subsequently asexually reproduced via tissue culture propagation and regeneration of artichoke plants from plantlets. The present variety has been found to be stable and reproduce true to type through successive asexual propagations.

'PAGA 13-1' exhibits the following distinguishing characteristics when grown under normal horticultural practices in Castroville, Calif.:

1. Large bud size;
2. Primary reproductive shoots produce at least 10 secondary buds, and at least 10 tertiary buds; on average, the number of lateral heads on the main stem of the plant ranges from 20 to 35;
3. Plants produce an average of 6 reproductive shoots, in addition to the primary reproductive shoot, during the first production cycle;
4. Bracts and receptacles are wide, and thick;
5. Large diameter peduncle; and
6. Late maturity.

DESCRIPTION OF THE DRAWINGS

The accompanying photographs illustrate the overall appearance of the new artichoke plant 'PAGA 13-1' showing the colors as true as is reasonably possible with colored reproductions of this type. Colors in the photographs may differ slightly from the color values cited in the detailed botanical description, which accurately describes the color of this variety. The depicted plant and plant parts of the new artichoke plant 'PAGA 13-1' are from plants that are 5-6 months old, grown in Castroville, Calif.

FIG. 1 shows various sized capitula (buds) of 'PAGA 13-1'.

FIG. 2 shows an interior view of a bract of 'PAGA 13-1'. FIG. 3 shows an exterior view of a bract of 'PAGA 13-1'.

FIG. 4 shows a cross section view of various sized capitula (buds) of 'PAGA 13-1'.

FIG. 5 shows various sized outer and inner bracts of 'PAGA 13-1'.

FIG. 6 shows a caulin and a basal rosette leaf of 'PAGA 13-1'.

FIG. 7 shows a growing field of 'PAGA 13-1' demonstrating its uniformity.

FIG. 8 shows a growing field of parent variety 'Green Globe' demonstrating its lack of uniformity.

FIG. 9 shows 'PAGA 13-1' capitulum (bud) bases showing the differences in purple colored striations on lower bracts.

FIG. 10 shows 'PAGA 13-1' (right) and 'Green Globe' (left) reproductive stems that have been stripped of leaves.

DETAILED BOTANICAL DESCRIPTION

The following detailed descriptions set forth the distinctive characteristics of 'PAGA 13-1'. The data which define these characteristics is based on observations taken in Castroville, Calif. This description is in accordance with UPOV terminology. Color designations, color descriptions, and other phenotypical descriptions may deviate from the stated values and descriptions depending upon variation in environmental, seasonal, climatic, and cultural conditions. 'PAGA 13-1' has not been observed under all possible environmental conditions. The botanical description of 'PAGA 13-1' was taken from plants that were 5-6 months old. The indicated values represent averages calculated from measurements of several plants. Color references are primarily to The R.H.S. Colour Chart of The Royal Horticultural Society of London (R.H.S.) (2007 edition). Descriptive terminology follows the *Plant Identification Terminology, An Illustrated Glossary, 2nd edition* by James G. Harris and Melinda Woolf Harris, unless where otherwise defined.

Classification:

Taxonomic name.—*Cynara cardunculus* L. var. *scolymus*.

Common name.—Globe Artichoke.

Denomination.—'PAGA 13-1'.

Parentage: *Cynara cardunculus* var. *scolymus* L. 'PAGA 13-1' was discovered through successive plant selections, and tissue culture propagation cycles of *Cynara cardunculus* L. var. *scolymus* variety 'Green Globe'.

TABLE 1

Plant Characteristics	
PAGA 13-1	
<u>General information</u>	
Propagation Method:	Tissue culture
Months of harvest:	Year round with greatest productivity April through July
Number of days from planting to first harvest	Range: 165-203 Average: 190 (tissue culture)
Duration of harvest cycle:	Average: 69 days
Plant	
Height range at harvest (vegetative):	162.56-198.12 cm (64-78 inches)
Height average at harvest (vegetative):	185.42 cm (73 inches)
Width at harvest (vegetative):	152.4-284.48 cm (60-112 inches)
Growth Habit:	Upright, with horizontal spread of older leaves and shoots
Form:	Arch
Vigor:	Very Good
Root system:	Thick and fibrous
Foliage Density:	Dense, increasing as secondary reproductive shoots develop
Male sterility:	Absent

TABLE 1-continued

Plant Characteristics	
Primary Reproductive Shoot	
Height to primary (terminal) bud top:	162.56-198.12 cm (64-78 inches)
Number of leaves (rosette)	25-33 (average 31)
Secondary Reproductive Shoots	
Number per plant in first production cycle:	4-10 (average 6)
Height to primary (terminal) bud top:	40.64-121.92 cm (16-48 inches)
Number of leaves	5-27 (average 7)
Foliage	
Venation:	Reticulate
Leaf ratio (L/W):	Approximately 1.1-3.23
Upper leaf surface color:	RHS 143A-143B (Green Group)
Lower leaf surface color:	RHS 141D (Green Group)
Leaf texture:	Glabrous and slightly glossy appearance in cool, damp conditions with interveinal texture.
Pubescence:	Slightly tomentose on upper surface, moderately tomentose on lower. More visible in dry/warm conditions.
Petiole color:	RHS 142B-142C (Green Group)
Petiole and mid rib texture:	Furrowed on upper side with lower side deeply ribbed with ridges running parallel to the lengthwise orientation. Sparsely arachnoid.
1. Basal rosette leaves	
Shape:	Deeply pinnatifid (i.e. strong lobing) with sparsely ciliate margins, narrowly trullate overall. Narrowly acuminate apex is less acute than Green Globe.
Size:	Very large, >198.12-78.74 cm (78 x 31 inches)
Distance between leaf division:	6.35-12.7 cm (2½-5 inches)
Division indentation length:	16.51-41.275 cm (6½-16¼ inches)
Petiole length:	30.48-57.15 cm (12-22½ inches)
Petiole width:	3.175-9.525 cm (1¼-3¾ inches)
Petiole thickness:	0.635-1.905 cm (¼-3/4 inches)
Midrib thickness:	Thick
2. Cauline leaves	
Shape:	Ensiform overall, uneven and sparse serrations with narrowly acuminate apex. Somewhat undulate and dented and sparsely ciliate at margins.
Number of leaves:	Approximately 93
Size:	17.78-60.96 cm (7-24 inches)
Stem (primary reproductive stem system)	
Length (ground level to base of terminal capitulum (bud)):	162.56-198.12 cm (64-78 inches)
Circumference: (base of terminal capitulum (bud)):	7.62-13.97 cm (3-5½ inches)
Circumference (base of stem):	Average: 36.83 cm (14½ inches)
Exterior texture:	Vertically ribbed, pubescent
Stem habit:	Upright, caulescent
Pubescence:	Sparsely arachnoid
Color:	RHS 142A-142B
Time of beginning of elongation:	Late

US PP32,119 P3

5

TABLE 1-continued

Plant Characteristics	
<u>Involucre bracts</u>	
Arrangement:	Imbricate
Quantity per Capitulum (average):	62 outer - 37 inner
Outer bract	
Shape:	Predominately ovate with flattened base
Apex:	Retuse with the tips curving down inside the capitulum
Margin:	Entire
Base:	Slightly rounded, thick
Texture:	Firm, thick and fleshy
Color:	RHS 142A-142B (Green Group)
Surface (outer/inner):	Glabrous
Spinosity:	Moderate frequency, woody
Length of spines:	1-5 mm (0.04-0.2 inches)
Striation at base of lower bracts:	Minor - present on lower outside bracts
Striation color:	RHS 77A (Purple-Violet Group)
Inner bract	
Shape:	Lanceolate with caudate tip
Apex:	Retuse with the tips curving down inside the capitulum
Margin:	Entire
Texture:	Firm, thinner than outer bract, fleshy
Base:	Slightly rounded
Color:	RHS 150B-150C (Green Group)
Surface (outer/inner):	Glabrous
Spinosity:	Finer than outer bract, more frequent
Length of spines:	1-2 mm (0.04-0.079 inches)
Capitulum (head/bud) - when ready for harvest as edible bud	
Color:	RHS 142A-142B (Green Group)
Shape:	Sub-globose with slightly flattened base and top
Apex:	Flat to concave
Base:	Truncate to rounded
Form:	Tightly compact
Texture:	Firm
Receptacle shape:	Concavo-convex
1. Primary (Terminal) Capitulum	
Number per primary shoot	1
Circumference:	32.385-38.1 cm (12 $\frac{3}{4}$ -15 inches)
Weight:	Average 425 grams (0.94 lbs.)
Height:	Average 10.16 cm (4 inches)
Diameter:	11.43-12.7 cm (4 $\frac{1}{2}$ -5 inches)
2. Secondary capitulum	
Number per primary shoot	10-19
Circumference	12.065-34.29 cm (4 $\frac{3}{4}$ -13 $\frac{1}{2}$ inches)
Weight:	Average 152 grams (0.3351 lbs.)
Height:	Average 7.62 cm (3 inches)
Diameter:	2.54-11.43 cm (1-4 $\frac{1}{2}$ inches)
3. Tertiary capitulum	
Number per primary shoot	10-16
Circumference	7.62-13.97 cm (3-5 $\frac{1}{2}$ inches)
Weight:	36 grams (0.07936 lbs.)
Height:	Average 5.08 cm (2 inches)
Diameter:	Average 5.08 cm (2 inches)
Receptacle (heart) - when ready for harvest and edible	
Shape:	Concavo-convex
Circumference:	8.89-25.4 cm (3 $\frac{1}{2}$ -10 inches)
Color:	RHS 150D (Green Group)
Texture:	Firm

35	
40	COMPARISON WITH PARENTAL AND COMMERCIAL VARIETIES
45	When artichoke plant 'PAGA 13-1' is compared to the parental variety 'Green Globe' (unpatented), 'PAGA 13-1' produces larger sized secondary and tertiary buds and in greater numbers. Additionally, 'PAGA 13-1' exhibits less phenotypic variation when grown in the field.
50	When artichoke plant 'PAGA 13-1' is compared to the commercial variety 'PAGA G-1' (U.S. Plant patent application Ser. No. 16/501,358), 'PAGA 13-1' produces at least 20 lateral buds on the primary reproductive shoots and on average 6 secondary reproductive shoots during the first production cycle, has a late maturity, and has a capitulum shape of sub-globose with slightly flattened base and top; whereas 'PAGA G-1' produces at least 9 lateral buds on the primary reproductive shoots and on average 3 secondary reproductive shoots during the first production cycle, has an early maturity, and has a capitulum shape of globose to ovoid.
55	When artichoke plant 'PAGA 13-1' is compared to the commercial variety 'PAGA 15-1' (U.S. Plant patent application Ser. No. 16/501,352), 'PAGA 13-1' produces at least 20 lateral buds on the primary reproductive shoots, on average 6 secondary reproductive shoots during the first production cycle, has a late maturity, and has a moderate frequency of spinosity on outer bract; whereas 'PAGA 15-1' produces at least 12 lateral buds on the primary reproductive
60	
65	

shoots, on average 4 secondary reproductive shoots during the first production cycle, has an early maturity, and has frequent spinosity on outer bract.

I claim:

1. A new and distinct variety of artichoke plant named 5
'PAGA 13-1' as shown and described herein.
